UNITED STATES PATENT OFFICE

JOHN PUGH BENNETT, OF WITTON, BIRMINGHAM, ENGLAND, ASSIGNOR TO HOOKLESS
FASTENER COMPANY, OF MEADVILLE, PENNSYLVANIA

SEPARABLE FASTENER

Application filed December 22, 1927, Serial No. 241,821, and in Great Britain April 12, 1927.

This invention relates to separable fasteners of the type in which two flexible stringers are adapted to be connected and disconnected by a plurality of interlocking jaw or other 5 fastener members cooperating with a sliding cam device mounted upon both members.

The object of the present invention is to devise improved means for rendering the two stringers completely separable instead of being 10 permanently attached to one another as is generally the case.

The invention consists in a fastener of the type referred to having novel separable connecting members at one end formed so that 15 a tooth or projection upon one member engages a correspondingly shaped recess or notch in the other member, so that when said members are enclosed within the slider cam, the stringer to which one of them is fastened 20 is movable longitudinally in relation to the cam and to the other stringer on which such cam device remains, to permit either of the complete separation of the stringers or of the proper positioning thereof to enable the 25 slider to function in the usual manner for locking and unlocking the fastener.

The invention also consists in a fastener according to the preceding paragraph in which the separable connecting members are 30 formed so that relative longitudinal movement in one direction is prevented while lateral separation is readily permitted when the connecting members are spread apart by the slider.

35 The invention also consists in the forms of fastener member hereinafter described or indicated.

The accompanying drawings illustrate two modes of carrying out the invention.

40 Figure 1 is an elevation of one form of separable fastener in accordance with the invention.

Figure 2 is a similar view showing the parts 45 completely separated and

Figures 3 and 4 are plan views respectively of Figures 1 and 2.

Figures 5 to 8 are similar views showing a somewhat modified form of fastener in accordance with the invention.

50 In carrying the invention into effect in one

convenient manner I form the fastener with two flexible stringers a' a'' having interlocking jaw members b' b'' of suitable form mounted thereon (as described, for example, in the specification of British Patent No. 55 12261 of 1915) and the usual or any desired form of slider cam device c having diverging channels is also provided in association with such stringers, there being if necessary or desirable a pull device d to facilitate manipulation of the slider cam. At that end of the fastener which is usually permanently closed a flat rectangular or other suitably shaped metal attachment is secured to each stringer, 60 one of these attachments e' having at that edge adjacent to the other stringer a triangular shaped notch e'' , the side of which nearest the chain of interlocking members is substantially at right angles to the edge, 70 while the other side may incline at a suitable angle (say, about 15 or 20°) to the edge. The other attachment e'' is provided with a correspondingly shaped triangular projection e'' which is furnished with a projecting tongue 75 e''' extending in a direction away from the chain. The thickness and combined width of these attachments or connecting members when engaged with one another are such that the over-all dimensions correspond with the 80 dimensions of the interlocking chain members when engaged (as shown in Figure 1) so that the slider cam device c can slide over the attachments and spread them apart until stopped in the manner hereinafter described. 85

Attached to the stringer a' carrying the notched fitting e' is another rectangular or other suitably shaped plate or stop member f lying in a plane at right angles to the above mentioned attachment and at right angles 90 to the stringers, and appropriately positioned in this plate I form two slots f' f'' of a key-hole shape, the outer ends being wide enough only to admit the tapes of the stringers while the inner ends are of circular form and are of 95 such diameter as will admit the corded edge of the tape at one side and the projecting tongue e''' of the attachment e'' on the other. The plate f is preferably provided with an integral flat portion f'' which is riveted to the 100

stringer a' and holds the plate firmly on the stringer as shown in Fig. 1.

When closing the fastener the sliding cam c which remains on the stringer a^1 as shewn in Figure 2, is moved along the stringer until it comes into contact with the slotted plate f , whereupon the tape of the other stringer a^2 is pulled in a downward direction, as viewed in the drawings, through the channels in the 10 sliding cam and slotted plate f until the tongue e^5 enters the circular portion of the slot f^2 . If now the slider is moved away from these attachments the triangular projection e^4 engages the corresponding notch e^2 thus 15 bringing the two stringers into correct relative position for the interlocking chain members to engage and on continuing the movement of the slider such chain members will interlock in the usual manner. A complete 20 separation of the stringers may be accomplished by a reversal of the operations described above.

Figures 5 to 8 represent a slightly modified form of fastener in accordance with the invention and similar parts in the two sets of views are denoted by similar reference characters. In this modification, however, the separate plate fitting f is omitted and is replaced by a projecting part of the fitting e' 30 in a circular aperture in which engages the projection e^5 , while there is also provided in this form of fastening a guiding tongue or member g upon the completely removable stringer, such member facilitating the entry 35 of the stringer into its proper position for the closing of the fastener by the slider cam and permitting of ready manipulation of such stringer when connecting or disconnecting the same.

40 It will be understood that the invention is not to be limited to the foregoing details of construction which are given purely by way of illustration since I may arrange the notched or recessed member on either of the 45 stringers with the tongued or like member upon the other, and I may vary the shape of such members and the means by which they are made to engage with one another depending upon the type or construction of fastener 50 to which the invention is to be applied or any practical requirements that may have to be fulfilled.

Having now particularly described and ascertained the nature of my said invention 55 and in what manner the same is to be performed, I declare that what I claim is:—

1. In a fastener adapted to be completely separated at both ends, a pair of stringers having cooperating interlocking members on 60 their adjacent edges, a slider having diverging channels movable along said stringers to engage and disengage said members, separable connecting members adjacent corresponding ends of said stringers adapted to 65 pass into the channels of said slider to be

spread apart thereby, cooperating angular notches and projections on the adjacent edges of said connecting members adapted when engaged to prevent longitudinal separation thereof, a stop member adjacent the end of one stringer to retain the slider on that stringer, a longitudinal recess in said stop member, and a longitudinal projection adjacent the end of the other stringer insertable into said recess to prevent lateral separation 70 and to position said interlocking members for engagement in the proper order, whereby said last mentioned stringer may be drawn lengthwise through said slider to effect complete separation of the stringers when said connecting members are spread apart. 75

2. In a fastener adapted to be completely separated at both ends, a pair of stringers having edgewise interlocking members, a slider movable along said stringers to engage and disengage said members, separable connecting members adjacent corresponding ends of said stringers adapted to enter said slider, a stop member fastened to one stringer beyond its connecting member to retain the slider on that stringer, and a slot in said stop member adapted to receive the edge of the opposite stringer to prevent edgewise separation of the stringers and to permit said opposite stringer to be drawn lengthwise through said slot and said slider when said interlocking members are disengaged. 90

3. In a fastener adapted to be completely separated at both ends, a pair of stringers having corded edges supporting cooperating interlocking members, a slider movable along said stringers to engage and disengage said members, separable connecting members adjacent corresponding ends of said stringers adapted to freely enter said slider, a stop member fastened to one stringer beyond its connecting member to retain the slider on that stringer, a slot in said stop member shaped to receive the corded edge of the opposite stringer when inserted lengthwise therethrough, and a projecting tongue on said opposite stringer insertable lengthwise into said slot to prevent edgewise separation of the stringers. 105

4. In a fastener adapted to be completely separated at both ends, a pair of stringers having cooperating interlocking members on their adjacent edges, a slider having diverging channels movable along said stringers to engage and disengage said members, separable connecting members adjacent corresponding ends of said stringers adapted to pass into the channels of said slider to be spread apart thereby, said connecting members having transversely flat contacting faces, one of said connecting members having a recess and the other of said connecting members having a cooperating projection on its contacting face adapted when said connecting members are engaged to prevent rela- 110 120 125 130

tive longitudinal movement of said connecting members and to guide said interlocking members into position for engagement in the proper order, a stop member adjacent 5 one of said connecting members to retain the slider on that stringer when the connecting members are disengaged, a longitudinal recess in said stop member, a longitudinal projection formed adjacent the end of the other 10 connecting member and insertable into said recess to prevent lateral separation of said connecting members, and to position said interlocking members for engagement in the proper order, whereby said connecting member 15 having the longitudinal projection may be drawn lengthwise through the slider to effect complete separation of said stringers when said connecting members are spread apart.

20 In testimony whereof I have signed my name to this specification.

JOHN PUGH BENNETT.
